CAULKING AND YARNING TOOL

Roy J. Behee, Leavenworth, Kans.

Application November 13, 1956, Serial No. 43,737

Term of patent 3½ years

(Cl. D93—4)

Fig. 1.

Fig. 2.

Fig. 3.

Fig. 4.

Fig. 1 is a perspective view of a caulking and yarning tool, showing one side thereof;

Fig. 2 is an elevational view showing the opposite side thereof;

Fig. 3 is an inverted fragmentary view showing the bottom thereof; and

Fig. 4 is a fragmentary plan view of the caulking and yarning tool.

The handle is shown broken away in Figs. 3 and 4 for convenience of illustration.

I claim:

The ornamental design for a caulking and yarning tool, as shown and described.
